ATTORNEY.

UNITED STATES PATENT OFFICE

MARTHA BRAZZELL, OF ST. LOUIS, MISSOURI

COMBINATION UNDERGARMENT FOR CHILDREN

Application filed February 15, 1929. Serial No. 340,070.

My invention relates to a combination undergarment for children of both sexes, and, it is a distinct and practical improvement to overcome certain practical objections to, and defects in, the present styles of children's undergarments.

The primary object of the invention is to provide a one piece undergarment wherein the waist line section of the back portion of the garment is buttoned to two buttons secured to the side edges of the chest portion of the garment at the waist line, and, wherein in the waist line of the back portion of the pants portion of the garment is buttoned to 10 the aforesaid buttons and to a central button secured to the waist line portion of the back portion of the garment.

A further object of the invention resides in the sewing of the back portion of the garment to the chest portion of the garment at the shoulder portion of the two garment sections adjacent the neck opening thereof.

A still further object of the invention is the provision of a combination undergarment 25 for children which possesses advantages in points of simplicity and efficiency, and, at the same time proves itself comparatively inexpensive in cost of manufacture.

With the above and other objects in view, 30 the invention consists in the novel features of construction, arrangement and combination of parts hereinafter more fully described and finally pointed out in the claim hereto appended.

35 Referring to the accompanying drawings forming a part of this specification, wherein like characters of reference denote similar parts throughout the several views:

Fig. 1 illustrates a front elevation of a 40 garment embodying my invention, the back body portion thereof being laid out flat.

Fig. 2 illustrates a rear elevation of the garment when fully buttoned, the dotted lines indicating the back body portion in its extended position.

Fig. 3 is a rear elevation similar to Fig. 1, with the upper part of the rear pants portion folded over and downwardly.

Fig. 4 is a front elevation of the garment.

50 Referring to the drawings, the reference

numerals 1, 1 designate a pair of like garment portions which are sewed together, as at 2, and provided at each side edge with a button 3 carried by a tape connection 4, or its equivalent. That portion of the garment portion 1, 1 above the buttons 3 and designated 5, 5 is the chest or front body portion of an undershirt, and, that portion of the garment portion 1, 1 below the buttons 3 and designated 6, is the front portion of the drawers which terminate downwardly in the short front leg portions 7, 7.

The upper edge of the chest portion 5, 5 of the undershirt is cut out, as at 8, to provide the front shoulder strap portions 9.

The reference numeral 10 designates the single back portion of the undershirt and it is cut out, as at 11, to provide the back shoulder strap portions 12 which are sewed to the front shoulder strap portions 9, thus in reality the back portion 10 becomes a continuation of the chest portion 5 in the nature of a flap. The cut out portions 8 and 11 of the chest and back portions of the undershirt provide a neck opening 13, as is apparent from Fig. 1, of the drawings.

A strip of tape 14, or its equivalent reinforcement, is sewed, as at 15, to the back portion 10 near its free or lower edge 16 and it is provided near each end, at the corners of the back portion 10, with the button holes 17. An outside button 18 is carried by the taped strip 14 midway its ends by means of a tape connection 18', or its equivalent.

The reference numbers 19, 19 designate two like back drawer portions which are sewed along their inner edges, as at 20, and which terminate downwardly therefrom in the short leg portions 21. The front and back leg portions of the drawers are provided with a crotch insert portion 22, which is sewed to the front leg portions, as at 23, and sewed to the back leg portions, as at 24.

The outer longitudinal edges of the back leg portions of the drawers are sewed to the front leg portions of the drawers, as at 25, which sewing extends from the lower outside edges of the back and front leg portions of the drawers to a point designated 26, thus permitting substantially the upper half of the

back drawer portions to act as a flap, which can be lowered.

The upper edge of the back drawer portions is provided with a suitable waist band 5 27. A button hole 28 is formed at each end of the waist band 27 for connection with the side buttons 3 which are connected to the side edges of the upper portion of the front drawer portions after the back portion 5 has been 10 connected to these buttons.

The waist band 27 is further provided with a third button hole 29 located, preferably midway the ends of the waist band 27 for connection with the button 18 of the back portion 5, thus it will be readily observed that the garment is only provided with three buttons and five button holes for detachably connecting the lower corners of the back portion of the undershirt to the outside edges of the 20 front portion of the drawers and connecting the upper corners of the back portion of the drawers to the outside edges of the upper front portion of the drawers and for connecting the middle of the upper edge of the back 25 portion of the drawers to the middle portion of the lower edge of the back portion of the undershirt portion of the combination undergarment.

The free outside edges of the combination 30 undergarment are preferably taped, as at 30, although it may be hemmed, or reinforced in well known equivalent manners.

The lower edges of the leg sections of the drawers are preferably, although not necessarily provided with concealed elastics 31.

From the foregoing description, it is evident that I provide a unit combination undergarment for children, that is a combined undershirt and drawers wherein the 40 back of the undershirt is a continuation of the chest portion thereof and designed for buttoned connection at its lower corners with the outside edges of the front part of the garment, preferably the drawer portion, and 45 wherein there is provided an additional button connection for buttoning the middle of the upper back flap portion of the drawers to the lower edge of the back portion of the undershirt section of the garment. Thus, it 50 will be readily appreciated that only three buttons are used in connection with my combination undergarment for children, yet providing a garment which is comparatively easy to manufacture, easy to get into, and easy 55 to get out of owing to the fact that only three buttons are to be contended with, and these so located that any child can readily button and unbutton the garment, as two of them are located to the side of the garment at the waist 60 line and one at the middle of the back of the garment.

It will be readily understood that as the outside edges of the front and back of the undershirt portion of the garment are not 65 connected, excepting by the side edge button

connections, that the arm holes are provided whenever these side button connections are made, thus the garment has large free arm holes which will in no way bind upon the child.

The many advantages of the herein described invention will readily suggest themselves to those skilled in the art to which it appertains.

From the foregoing description, it is evident that a simple garment for this purpose has been disclosed, but it is to be understood that I do not desire to restrict, or limit myself to the very details of the construction shown and described, which is merely illustrative, it being obvious that changes, not involving the exercise of invention, may be made without conflicting or departing from the spirit of the invention within the scope of the appended claim.

What I claim is:

A combination undergarment for children comprising a pants portion and a waist portion, the front part of the waist portion being continuous with the front part of the pants portion and the back part of the waist portion being continuous with the front waist portion and said front and back waist portions being provided with a neck opening, the upper half of the back part of the pants portion being non-connected to the front part of the pants portion to provide a flap portion, the lower corners of the back waist portion being provided with button holes, a pair of buttons connected with the side edges of the upper front part of the pants portion for the button holes at the lower corners of the back waist portion, the upper corners of the flap portion of the back part of the pants portion being provided with button holes for the same buttons as the corner button holes of the back part of the waist portion, the upper edge of the flap portion of the back part of the pants portion being provided with a button hole midway the corner button holes thereof and a button sewed to the lower edge portion of the back part of the waist portion midway the corner button holes thereof for the button hole midway the corner button holes of the back flap portion.

In testimony whereof, I have hereunto affixed my signature.

MARTHA BRAZZELL.
